CLAIM

The ornamental design for an ice pack headband as shown and described.

DESCRIPTION

FIG. 1 is a front view of an ice pack headband showing my new design;

FIG. 2 is a rear view thereof;

FIG. 3 is a top plan view thereof;

FIG. 4 is a left side elevational view thereof;

FIG. 5 is a right side elevational view thereof; and,

FIG. 6 is a bottom plan view thereof.

The broken lines shown in FIG. 1 illustrate portions of the ice pack headband that form no part of the claimed design.
